Primary Examiner — Richard Kearney*Assistant Examiner* — Christina M. Dodson(74) *Attorney, Agent, or Firm* — Calfee, Halter & Griswold LLP(57) **CLAIM**

I claim the ornamental design for a light, as shown and described.

DESCRIPTION

FIG. 1 is a front/right/top perspective view of a light; FIG. 2 is a front elevational view thereof; FIG. 3 is a right side view thereof, a left side view being a mirror image thereof; FIG. 4 is a top plan view thereof, a bottom plan view being a mirror image thereof; FIG. 5 is a rear elevational view thereof; FIG. 6 is a front/right/top perspective view of a second embodiment of FIG. 1, the only difference being the configuration of the front panel, it being understood that all other surfaces are the same as those of the first embodiment; FIG. 7 is a front elevational view of the second embodiment; and, FIG. 8 is an inset view of the indicated portion 8 of the light of FIG. 1.

The broken lines illustrate portions of the light that form no part of the claimed design. The dot-dot-dash lines illustrate the boundary of the enlarged view and form no part of the claimed design.
